UNITED STATES PATENT OFFICE.

ARTHUR M. HOOD, OF INDIANAPOLIS, INDIANA, ASSIGNOR, BY MESNE ASSIGNMENTS TO WIREBOUNDS PATENTS COMPANY, A CORPORATION OF MAINE.

WIRE-BOUND COOP.

1,383,119.

Specification of Letters Patent. Patented June 28, 1921.

Application filed October 11, 1915. Serial No. 55,144.

To all whom it may concern:

Be it known that I, ARTHUR M. HOOD, a citizen of the United States, residing at Indianapolis, in the county of Marion and 5 State of Indiana, have invented a new and useful Wire-Bound Coop, of which the following is a specification.

The object of my invention is to produce a wirebound box or crate equipped with 10 sliding doors, the construction being such that comparatively light, cheap material may be utilized and the sliding doors readily associated with the other material at the time of production of the foldable blank.

15 The accompanying drawings illustrate my invention. Figure 1 is a perspective view of the completed crate or box in such form as to be convenient for use in handling poultry; Fig. 2 a plan of the middle portion of 20 the door section; Fig. 3 a view similar to Fig. 2 showing one of the doors open; Fig. 4 a section on line 4-4 of Fig. 3; Fig. 5 a section on line 5-5 of Fig. 3; Fig. 6 a 25 plan of the complete blank in the flat; and Fig. 7 a perspective view of the completed crate or box, showing the binding wires extending across but not attached to the doors.

In the drawings, 10 indicates a series of 30 slats connected at their ends by cross bars 11 which are arranged in pairs upon opposite faces of the slats and have a length exceeding the width of the space occupied by the slats, these slats being conveniently separated a distance slightly greater than 35 the width of the slats. 12 indicates a series of slats interdigitated between slats 10, and these slats 12 are connected at their ends by cross bars 13 arranged in pairs and having lengths substantially equal to the lengths 40 of bars 11, one of the pairs of bars 13 lying between the two pairs of bars. The door structure just described will be made up as a separate unit and in order that the parts may slide readily it is desirable that one set 45 of bars, as, for instance, the bars 10, be slightly thicker than the other set, as indicated in Fig. 5. In that case, thin shims will be placed under those bars 13 which lie between the bars 11 in order to permit 50 the bars 10 to slide freely between those bars 13. The door-carrying section of the crate will comprise end cleats 15, 15, a central intermediate cleat 16, and if the crate 55 is of considerable length, intermediate cleats 17, 17, all of these cleats preferably being

formed at their ends for mating engagement with cleats of an adjacent section of the blank, as, for instance, with mortise and tenon ends. If the intermediate cleats 17 are used, they will be provided upon their 60 outer edges at suitable points with notches 18 which will permit the passage of the under cross bars 13 or 11, as clearly indicated in Fig. 5. In assembling the blank and assuming the door-carrying section to 65 be one of the initial sections of the blank, the slats 19 will be applied to the cleats 15, 16 and 17 and held thereon by the usual staples 20 and connecting binding wires 21. When the proper point has been reached, 70 the door section, comprising the two doors, will have associated therewith two of the slats 19, as indicated in Fig. 3, and these two slats 19 with the intermediate door sections, will be attached to the cleats in 75 the same manner, the intermediate binding wires, if desired, passing over the door sections, but the staples being omitted. The operation will, of course, be exactly the same even though the door-carrying section 80 be an intermediate section of the blank, as shown in Fig. 6. Flanking the door-carrying section are the two side sections S, S (Fig. 6) and comprising cleats 15, 16 and 85 17 corresponding with the cleats of the door-carrying section, and also comprising slats 19. The bottom section B comprises cleats 15, 16 and 17 and bottom boards 22, the several elements being associated by means of the staples 20 and binding wires 21, the parts 90 being assembled in the flat, as indicated in Fig. 6. With the blank thus formed, the parts may be folded in the usual manner to form the top, bottom and two sides of the box or crate, the cleats engaging each other 95 in the usual manner and binding wires serving to hold the parts firmly bound together, the adjacent ends of these binding wires being twisted together in the usual manner, if desired. 100

It will be understood that the intermediate cleats 17 of the sides and bottom need not be notched in the manner in which they are notched for the top section T. Suitable end sections E may then be placed and secured to the inner faces of the end cleats 15 and, if desired, partition slats P may be secured to the intermediate series of cleats 16. In order to facilitate the sliding of the door sections, the intermediate binding wires 105 100

20, if they have been projected across the door sections, may be cut away, as indicated in the drawings.

It will be noticed that by the construction 5 shown, the door-carrying section is, within itself, rigid so that no additional cleats need be provided in order to make the door-carrying member sufficiently rigid.

I claim as my invention:

10 1. A wirebound box or crate blank, comprising a plurality of independent cleated sections foldably associated by means of binding wires, one of said sections comprising two parallel members lying transversely 15 of the binding wires and held in spaced relation by cleats associated with said members and the binding wires, and two interdigitated sliding doors lying between the spaced members and interlocked therewith, said 20 doors being slideable in opposite directions between and parallel with the parallel members.

2. A wirebound box or crate blank, comprising independent cleated sections foldably associated by means of binding wires, one of said sections comprising two substantially parallel members held in spaced 25 relationship by cleats, and a slideable door section slideable between and parallel with 30 the substantially parallel members and associated therebetween at the time the binding wires, cleats and parallel members are connected together.

3. A wirebound box or crate blank, comprising a cleated bottom section, two cleated side sections, and a cleated top section, said several sections being connected and bound together by binding wires overlapping and fastened to the cleats in such manner that 40 the sections may be folded together to form a container; one of said sections comprising two slideable integral door sections interdigitated with each other and interlocked with adjacent portions of said section and 45 associated with the adjacent portions of the section at the time of assembly of the sections into blank form.

4. A wirebound box or crate blank comprising a bottom section, two side sections, 50 and a top section, said several sections being connected and bound together by binding wires in such manner that the sections may be folded together to form a container; one of said sections comprising two slideable integral door sections interdigitated with each other and interlocked with adjacent 55 portions of said sections and associated with the adjacent portions of the section at the time of assembly of the sections into blank form.

5. A wirebound box or crate blank comprising a cleated bottom section, two cleated side sections, and a cleated top section, said several sections being connected and bound together by binding wires overlapping and 65 fastened to the cleats in such manner that the sections may be folded together to form a container; one of said sections comprising two slideable integral door sections interdigitated with each other and interlocked 70 with adjacent portions of said section and associated with the adjacent portions of the section at the time of assembly of the sections into blank form and overlaid by the intermediate binding wires of the blank. 75

6. A wirebound box or crate blank comprising a bottom section, two side sections, and a top section, said several sections being connected and bound together by binding wires in such manner that the sections may 80 be folded together to form a container; one of said sections comprising two slideable integral door sections interdigitated with each other and interlocked with adjacent portions of said section and associated with the 85 adjacent portions of the section at the time of assembly of the sections into blank form and overlaid by the intermediate binding wires of the blank.

7. A crate section comprising a plurality 90 of facing members, a plurality of transverse connecting members, and transverse binding wires, two of the facing members being spaced apart a distance suitable for forming an access opening, and two interdigitated and sliding door members slideable 95 each into the same lateral relationship with adjacent parts as its fellow, said door members having interlocking engagement with adjacent portions of the section to prevent 100 withdrawal from the section and being overlaid by binding wires.

8. A crate section comprising a plurality of facing members, a plurality of transverse connecting members, and transverse 105 binding wires, two of the facing members being spaced apart a distance suitable for forming an access opening, and two interdigitated and sliding door members slideable 110 each into the same lateral relationship with adjacent parts as its fellow, said door members having interlocking engagement with adjacent portions of the section to prevent withdrawal from the section.

In witness whereof, I have hereunto set 115 my hand at Indianapolis, Indiana, this 9th day of October, A. D. one thousand nine hundred and fifteen.

ARTHUR M. HOOD.
